UNITED STATES PATENT OFFICE

162,046

ANIMAL MARKER OR SIMILAR ARTICLE

Ronald Harvey David Frank Lee, Berkhamsted, England, assignor to Cooper, McDougall & Robertson Limited, Berkhamsted, England, a British company

Application July 30, 1949, Serial No. 4,227
In Great Britain May 4, 1949

Term of patent 14 years

(Cl. D12—2)

To all whom it may concern:

Be it known that I, Ronald Harvey David Frank Lee, a subject of the King of England and a resident of the city of Berkhamsted, in the county of Hertfordshire, England, have invented a new, original, and ornamental Design for an Animal Marker or Similar Article, of which the following is a specification, reference being had to the accompanying drawing, forming a part thereof.

I claim:

The ornamental design for an animal marker, or similar article, as shown.

RONALD HARVEY DAVID FRANK LEE.
